UNITED STATES PATENT OFFICE.

AXEL HERMANSEN, OF INGELSTAD, SWEDEN.

OPEN-HEARTH FURNACE.

Application filed June 26, 1924. Serial No. 722,495.

To all whom it may concern:

Be it known that I, AXEL HERMANSEN, a subject of the Kingdom of Denmark, residing at Ingelstad Gard, Ingelstad, Sweden, 5 have invented a certain new and useful Improvement in Open-Hearth Furnaces, of which the following is a full, clear, and exact description.

My invention relates to furnaces, and has 10 special reference to open hearth furnaces of the type employing recuperators that are in communication with the open ends, respectively, of the melting chamber, for utilizing the heat of the waste gases passing from the 15 melting chamber for the purpose of heating air and directing the heated air into the melting chamber to support combustion. In furnaces of this type it is not possible to utilize in the recuperators all of the heat 20 value in the waste gases, and, consequently, in such furnaces as heretofore constructed a large portion of the heat value in the gases is wasted.

An object of the present invention is to 25 provide a furnace of the character indicated which is capable of being so operated that only a sufficient quantity of the waste gases pass to the recuperators as is necessary to supply the requisite degree of heat for their 30 most efficient operation, while the rest of the waste gases pass to other heat absorption apparatus and thus is put to practical use.

Another object of the invention is to provide an open hearth furnace of the recuperative type which is of simple and compact construction, and economical and highly efficient in operation.

The several features of the invention, 40 whereby the above mentioned and other objects may be attained, will be clearly understood from the following description and accompanying drawings, in which,

Figure 1 is a longitudinal sectional elevation taken substantially on the line 1—1 of 45 Fig. 2 of an open hearth furnace of the recuperative type embodying the features of the invention;

Fig. 2 is a sectional plan view taken on the line 2—2 of Fig. 1;

50 Figs. 3 and 4 are transverse sectional views taken on the lines 3—3 and 4—4, respectively, of Fig. 2;

Fig. 5 is a sectional plan view taken on the line 5—5 of Fig. 4; and

Fig. 6 is a diagrammatical view of the furnace.

The recuperative open hearth furnace illustrated in the drawings is provided with a melting chamber 2 having the usual longitudinally curved hearth 4, top wall or arch 6, and front and rear side walls 8 having suitably arranged charge openings 10 and discharge or tapping holes 12. Each end of the melting chamber is divided by a vertical partition to provide passages 14 and 16. The 60 passages 14 lead outwardly a distance and then downwardly to a point substantially midway of the top and bottom walls of the furnace, where they are in communication with each other through a passage 18 extending longitudinally of the furnace, where they are in communication with each other through a passage 18 extending longitudinally of the furnace. The passage 18 is in communication through passages 20 with the 65 air outlet ends of recuperators 24 and 26 which are arranged adjacent the left and right hand ends, respectively of the furnace, and are mounted on the bottom wall of the furnace a distance in front of the melting 70 chamber 2. Air is admitted to each of the recuperators through conduits 28 leading into the air inlet end of the recuperator and provided with a sliding damper 30.

The passage 16 in the right hand end of 75 the melting chamber extends a distance outwardly, then vertically downwardly to the bottom of the furnace, and then forwardly beneath the lower end of the adjacent passage 14 to the gas inlet end of the recuperator 26. The gas outlet end of this recuperator is in communication through a passage 80 85 90 95 22 with the inlet opening 34 of a boiler chamber 36 in which is arranged a water tube boiler 38. This boiler chamber is provided with a gas outlet passage 40 which leads through a flue 42, having a sliding damper 44, to a stack 46.

The passage 16 in the left hand end of the melting chamber extends outwardly, then downwardly to the bottom of the furnace, then forwardly beneath the lower end of the adjacent passage 14, and then inwardly to the gas inlet opening 48 of a furnace chamber 50 in which there is mounted a water tube boiler 52. The gas outlet opening 54 of this furnace chamber is in communication through a passage 56 with the gas inlet end 100 105

of the recuperator 24. The gas outlet end of this recuperator is in communication through a flue 58, having a sliding damper 60, with the stack 46.

5 Oil, producer gas or other suitable fuel is admitted to the melting chamber through valve-controlled pipes 62 which extend downwardly into the passages 14 adjacent the ends of the chamber.

10 In the operation of the furnace, fuel is admitted through both of the supply pipes 62 at the same time and is ignited. The ignited fuel in the two passages 14 each traverse a more or less of a horse shoe path, as indicated by arrows in Figs. 2 and 6, to substantially the center of the smelting chamber, and then out through the adjacent gas outlet passage 16. The hot gases entering the discharge passage 16 at the 15 right hand end of the melting chamber, pass through said passage to the recuperator 26, and after passing through the recuperator pass out through the passage 32, through the boiler 38, and then out through the flue 20 42 to the stack 46. The hot gases entering the passage 16 at the left hand end of the melting chamber, pass through this passage to the boiler 52, and after passing through the boiler pass through the passage 56, the 25 recuperator 24, and out through the flue 58 to the stack 46.

The air entering the recuperators 24 and 26 through the passages 28 pass through the passages 20, respectively, to the common 30 passage 18 where the two streams of air meet to effect equalization of temperature thereof. Air from the common passage 18 then passes at a substantially uniform temperature up through the passages 14 where 35 it mixes with the fuel from the supply pipes 62 to support combustion.

40 From the foregoing it will be apparent that the waste gases passing from the right hand end of the furnace chamber pass first 45 through a recuperator where a substantial part of the heat value thereof is given up to the air entering the recuperator, and then passes through a waste heat boiler which absorbs as much as possible of the remaining 50 amount of heat value in the gases, before the gases pass to the stack; and that the hot gases passing from the left hand end of the furnace pass first through the water tube boiler 52 where a substantial 55 part of the heat value of the gases is given up, and then passes through the recuperator to the stack. By this arrangement it is possible for the recuperators and boilers to absorb all of the heat value of the waste 60 gases with the exception of a sufficient degree of heat being left in the gases to effect the necessary stack draft. Also, by arranging the recuperators and boilers as described, one of the boilers receives the direct 65 heat of the waste gases emerging from one

end of the melting chamber, and one of the recuperators receives the direct heat of the hot gases emerging from the other end of the chamber. By mixing the two streams of heated air passing from the recuperators 70 so as to equalize their temperature, and then distributing the air equally to the gas inlet passages 14 of the melting chamber, uniform working conditions are effected in both ends of the melting chamber. 75

The recuperators and waste heat boilers are all arranged beneath a horizontal wall 64 which is spaced a distance below the charge openings 10 of the melting chamber and projects forwardly from the front side 80 wall of the melting chamber, which provides a compact construction in which the recuperators and boilers are all enclosed by a single wall which may be of high heat insulating material, and the arrangement of 85 these apparatus in front of the melting chamber permits easy access thereto. With the arrangement of the recuperators and boilers as illustrated in the drawings, the waste gases will enter the recuperator 26 90 and the boiler 52 at substantially the temperature that they leave the melting chamber. It may be noted that the dampers 30, 44 and 60 are all located beyond the recuperators and boilers so that none of them 95 is subjected to the intense heat of the waste gases leaving the melting chamber.

As will be evident to those skilled in the art, my invention permits of various modifications without departing from the spirit 100 thereof or the scope of the appended claims.

What I claim is:

1. A furnace of the class described having, in combination, a melting chamber, recuperators associated with the ends of said chamber, respectively, heat absorption apparatus associated with the ends of the chamber, respectively, and suitable means for conducting waste gases from one end of said chamber first through the recuperator and then through the heat absorption apparatus associated therewith, and for conducting hot gases from the other end of the chamber first through the heat absorption apparatus and then through the recuperator associated therewith. 105 110 115

2. A furnace of the class described having, in combination, a melting chamber, recuperators associated with the ends of said chamber, respectively, heat absorption apparatus associated with the ends of the chamber, respectively, and suitable means for conducting waste gases from one end of said chamber first through the recuperator and then through the heat absorption apparatus associated therewith, and for conducting waste gases from the other end of the chamber first through the heat absorption apparatus and then through the recuperator associated therewith, and means 120 125 130

for equalizing the temperature of the heated air passing from the recuperators and then directing it into the melting chamber through both ends thereof.

5 3. A furnace of the class described having, in combination, a melting chamber, recuperators associated with the ends of said chamber, respectively, heat absorption apparatus associated with the ends of the 10 chamber, respectively, suitable means for conducting waste gases from one end of said chamber first through the recuperator and then through the heat absorption apparatus associated therewith, and for conducting 15 waste gases from the other end of the chamber first through the heat absorption apparatus and then through the recuperator associated therewith, a conduit connecting the air outlet ends of said recuperators, and 20 means for directing air from said conduit into the melting chamber through both ends thereof.

4. A furnace of the class described having, in combination, a melting chamber, a 25 recuperator associated with one end of the chamber, a heat absorption apparatus associated with the other end of the chamber, means for conducting waste gases from the first mentioned end of the chamber to said 30 recuperator, means for conducting waste gases from the other end of the chamber to said heat absorption apparatus, and means for conducting heated air from the recuperator to the melting chamber.

35 5. A furnace of the class described having, in combination, a melting chamber, a recuperator associated with one end of the chamber, a heat absorption apparatus associated with the other end of the chamber, 40 means for conducting waste gases from the first mentioned end of the chamber to said recuperator, means for conducting waste gases from the other end of the chamber to said heat absorption apparatus, and means 45 for conducting heated air into the melting chamber through both ends thereof.

6. A furnace of the class described having, in combination, a melting chamber having a fuel inlet opening and a waste gas outlet 50 opening in each of its ends, a recuperator having its gas inlet end in communication with said waste gas outlet in one of the ends of the chamber, a heat absorption apparatus having its gas inlet end in communication 55 with the gas outlet end of said recuperator, a second heat absorption apparatus having its gas inlet end in communication with the waste gas outlet in the other end of said melting chamber, a second recuperator having its gas inlet end in communication 60 with the gas outlet end of said last mentioned heat absorption apparatus, and means for bringing the heated air passing

from said recuperators together and then directing it into said melting chamber through 65 both of said fuel inlet openings.

7. A furnace of the class described having, in combination, a melting chamber, recuperators associated with the ends of the chamber, respectively, means for directing 70 waste gases from the ends of said chamber through said recuperators, and means for mixing the heated air passing from said recuperators and then directing it into said chamber through both ends thereof. 75

8. A furnace of the class described having, in combination, a melting chamber having a fuel inlet and a waste gas outlet in each of its ends, and a recuperator having its gas inlet in communication with the waste 80 gas outlet in one end of said chamber, and having its air outlet in communication with the fuel inlet in both ends of said chamber.

9. A furnace of the class described having, in combination, a melting chamber having a fuel inlet and a waste gas outlet in each of its ends, a recuperator having its gas inlet in communication with the waste gas outlet in one end of said chamber, and having its air outlet in communication with the fuel inlet in said end of the chamber, a heat absorption apparatus having its gas inlet in communication with the gas outlet of said recuperator and having a flue provided with a damper leading from its flue 95 gas outlet, a second heat absorption apparatus having its gas inlet in communication with the waste gas outlet of the other end of said melting chamber, a recuperator having its gas inlet in communication with the gas outlet of said second mentioned heat absorption apparatus, a flue provided with a damper leading from the gas outlet end of said second mentioned recuperator, and a conduit connecting the air outlets of said 100 recuperators and in communication with the fuel inlet in both ends of the melting chamber. 105

10. A furnace of the class described having, in combination, an elongated melting 110 chamber having its front wall provided with charge openings, recuperators located adjacent and in front of the ends of said melting chamber, waste heat absorption apparatus located between said recuperators, said 115 recuperators and waste heat absorption apparatus being adapted to be heated by the waste gases passing from said melting chamber, and an enclosure for said recuperators and waste heat absorption apparatus having 120 its top wall spaced a distance below the charge opening in the front wall of said melting chamber and projecting forwardly therefrom.

AXEL HERMANSEN.
